UNITED STATES PATENT OFFICE.

JAMES ERICKSON, OF PHILADELPHIA, PENNSYLVANIA.

PILE-DRIVING MECHANISM.

1,131,048.

Specification of Letters Patent.

Patented Mar. 9, 1915.

Application filed May 5, 1914. Serial No. 836,395.

To all whom it may concern:

Be it known that I, JAMES ERICKSON, a citizen of the United States, residing in Philadelphia, county of Philadelphia, State 5 of Pennsylvania, have invented certain new and useful Improvements in Pile-Driving Mechanism, of which the following is a specification.

This invention relates to a pile driving mechanism, and has for an object to provide a device for driving piles which may be employed for vertical pile driving or for accurately driving a pile or piles at an angle to the vertical.

15 It has for a further object to provide a device wherein the height of the driver frame may be adjusted so that piles of different lengths may be used in connection with the mechanism without decreasing the 20 efficiency or lessening the effective impact of the driving ram.

It further consists of other novel features of construction all as will be hereinafter fully set forth.

25 For the purpose of illustrating my invention, I have shown in the accompanying drawings one form thereof which is at present preferred by me, since the same has been found in practice to give satisfactory and reliable results, although it is to be understood 30 that the various instrumentalities of which my invention consists can be variously arranged and organized and that my invention is not limited to the precise arrangement and 35 organization of these instrumentalities as herein shown and described.

In the drawings:—Figure 1 represents a side elevation of a pile driver embodying 40 my invention; Fig. 2 represents a vertical section of a portion of the device; Fig. 3 represents a side elevation of the top portion of the boom arranged for use as a hoisting mechanism; Fig. 4 represents a plan of the pile driver; Fig. 5 represents a 45 transverse section showing the auxiliary guy frame; Fig. 6 represents a section on the line $x-x$ of Fig. 1; and Fig. 7 represents a section on the line $y-y$ of Fig. 1.

50 1 designates a pair of beams forming the main supporting base of the device and which are adapted to be firmly secured upon a suitable support, such as a scow 2 or float, although it will be understood that this may be replaced by any suitable form 55 of support. These beams 1 project beyond

the support 2 and form what may be termed a throat to receive the pile driving mechanism and through which the pile to be driven is adapted to pass.

3 designates a boom suitably pivoted at 60 4 to the supporting structure and carrying at its upper end trunion plates 5 adapted to receive a pin 6 which passes through the apertured plates or ears 7 fixed to a suitable portion of the driver frame. This driver 65 frame consists of a pair of beams 8 suitably spaced apart and braced at intervals by the tie braces 9.

10 designates guides or guide rails secured to the beams 8 and provided with rails or 70 guides 11 adapted to coöperate with the monkey or ram 12 which is slotted at the sides for the purpose readily apparent.

The beams 8 are also preferably braced by the truss 13 which is further reinforced 75 by stay-rods 14, the latter tying the truss to the main pile driver frame.

15 and 16 designate sheaves located respectively at the upper and lower ends of the driver frame and about which the rope 80 or cable 17 passes for connection with the ram 12. It will also be noted that a guide pulley 18 is mounted between the plates 5 and is free to rotate upon the pin 16 in order to properly guide and prevent displacement of the cable 17. The cable 17 is connected to the ram 12 by any suitable type of mechanism such as a striker-off or the like for releasing the ram, but as this connecting means forms no part of the present invention 90 I have merely shown a conventional type of fastening between the ram and the said cable.

19 designates a ladder frame having 95 rounds or step bars 20, all of which structure is fixed to the driver frame and enables the operator or user to gain access to the different parts of the frame for purposes of repair or adjustment.

21 designates a pair of masts forming 100 with the brace bars 22 an A-frame, carrying at the upper end suitable supports for a clevis member 23 which carries a pulley block 24 about which a cable 25 passes for raising and lowering the boom 3. A similar 105 block mechanism 26 is suitably supported at the upper end of the boom 3 and the cable passes about this lower member and substantially parallels the boom to a point adjacent the lower end where it passes about a fixed 110

pulley 27 to a suitable hoisting mechanism not illustrated.

28 designates a tie-rod connected at one end to the upper portion of the A-frame, 5 and at its lower end to the fixed support, whereby the frame and its adjuncts are fixedly secured in operative position.

By reference to Fig. 6 it will be seen that the pile 29 when in position to be driven, 10 is located between the beams 8 and the guides in which position it is directly in the path of movement of the ram 12. For the purpose of maintaining the pile properly located with respect to the driver frame 15 and the ram, I have provided a pair of brackets 30 which are secured to the respective guide members 10, and extend laterally therefrom, each having a recessed portion to receive the bar 31 which serves as a holder 20 to prevent the pile from being displaced. It will further be noted that the lower extremity of each of the beams 8 is provided with a plurality of apertures 32 to receive a fastening bolt 33 or like device which passes 25 through the respective beams 1 and thus maintains the driver frame properly located within the throat. These apertures 32 form a means for adjusting the driver as to height and as the bolts 33 form pivots, the 30 said frame when once located in the desired opening 33 may be swung to any desired angle so that the pile may be driven in a position other than the vertical if desired. This swinging of the frame about the pivots 33 is accomplished by raising or lowering 35 of the boom 3 through the lower devices controlling the cables 25.

In Fig. 3 I have shown a modified form 40 of a device wherein by employing a sheave 34 positioned at a suitable point on the boom 3 the cable 17 may be passed thereover and its free end attached to a dredging device, clam forks or like apparatus.

In the operation of the device the A- 45 frame and its supports, together with the boom and throat beams, are suitably fixed in position adjacent the point where the piles are to be driven, after which the driver frame is located for height by adjusting 50 the bolts 33 in the proper openings 32. If the piles are to be driven vertically the boom 3 is power actuated to raise the frame and maintain it in a vertical position, and the device is then ready for the successive placing 55 of the piles. The retaining bar 31 is then removed so that the pile may be properly located within the frame and in the path of the ram, and in this position it is held by replacing the bar 31 as shown in Fig. 6. The actuation of the machine takes 60 place as in the ordinary type of pile driver, the ram being raised by power, released and dropped by gravity. In case the piles are to be driven at an angle the driver frame, 65 after a pile has been placed in position with-

in the frame, may be shifted to the desired angle by swinging the boom until it is properly adjusted and where it may be held accurately during the pile driving operation.

It will now be apparent that I have devised a novel and useful construction which embodies the features of advantage enumerated as desirable in the statement of the invention and the above description, and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

I claim:—

1. In a device of the character stated, a base, a driving frame pivotally connected to said base, means for pivotally connecting said frame at different points longitudinally thereof to said base whereby it may be longitudinally adjusted, a boom connected to one end of said frame, a ram mounted for sliding movement on said frame, power transmitting means for raising and lowering the upper end of said boom to raise and lower the upper end of said frame to vary the angular position thereof relative to said base, a fixed frame to which the power actuating means is connected and means for holding a pile in the path of movement of said ram regardless of the angular position of said frame.

2. In a device of the character stated, a base adapted to be secured to a suitable support and arranged to form a throat, a driving frame having one end positioned within said throat, pivotal connections between said base and said frame whereby the latter may be swung forwardly and rearwardly, said pivotal connections being adjustable, guides on said frame, a ram mounted to slide on said guides, a transversely arranged bar adjacent one end of said frame for maintaining a pile in position within the path of movement of said ram regardless of the angular position of said frame, said bar being movable from one position to another so that a pile may be placed in position, and power actuated means for raising and lowering the upper end of said frame to vary its position of angularity with respect to said base.

3. In a device of the character stated, a base, a driving frame formed by a pair of substantially parallel beams spaced apart, each beam having a plurality of openings, pivot means adapted to pass through any one of said openings and secure said frame to said base, a pair of brackets secured at one side of said frame, a bar removably car- 130

ried by said brackets and adapted to close a portion of the space between said beams in order to hold a pile to be driven in proper position, a ram slidably mounted in said 5 frame and power actuated means for controlling the actuation of said ram.

In testimony that I claim the foregoing

as my invention I have hereunto signed my name this 2d day of May, A. D. 1914.

JAMES ERICKSON.

In the presence of—

HORACE D. REEVE,

CARRIE E. KLEINFELDER.
